(57) **CLAIM**

The ornamental design for a lint filter, as shown and described.

DESCRIPTION

FIG. 1 is a front perspective view of a lint filter according to the present invention.

FIG. 2 is a top view of the lint filter of FIG. 1.

FIG. 3 is a first side view of the lint filter of FIG. 1.

FIG. 4 is a second side view of the lint filter of FIG. 1, opposite the first side shown in FIG. 3.

FIG. 5 is a front view of the lint filter of FIG. 1.

FIG. 6 is a rear view of the lint filter of FIG. 1; and, FIG. 7 is a bottom perspective view of the lint filter of FIG. 1.

The shading lines are for illustrative purposes only and form no part of the claimed design.
